(57) **CLAIM**

The ornamental design for a receptacle connector, as shown and described.

DESCRIPTION

FIG. 1 is a perspective view of a receptacle connector showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view of the receptacle connector showing our new design; and,

FIG. 9 is a third perspective view of the receptacle connector showing our new design.

The broken line portion of the figure drawings is included to show unclaimed subject matter only and forms no part of the claimed design.
